COMBINED SOFA-BED DRAWER AND BIN

Jack M. Radinsky, Denver, Colo., assignor to A. D. Radinsky & Sons, Inc., Denver, Colo., a corporation of Colorado

Filed July 6, 1961, Ser. No. 65,854

Term of patent 14 years

(Cl. D15—11)

Fig. 1

Fig. 2

Fig. 3

Fig. 4

FIGURE 1 is an isometric view of my design for a combined sofa-bed, drawer and bin as viewed towards the front and one side thereof.

FIGURE 2 is an isometric view of the design as viewed towards the rear and the opposite side thereof.

FIGURE 3 is an isometric view, similar to FIG. 1 but with the bed portion being extended, the drawers being partially open and the bin lid being opened.

FIGURE 4 is an isometric view, similar to FIG. 2, but with the bed portion being extended, the drawers being partially open and the bin lid being opened.

The essential feature of my design resides in the provision of the three-cushion arrangement wherein each cushion forms the facing of a shallow drawer, in combination with the single arm pull-out bed and rear top opening storage compartment behind the drawers, as shown.

I claim:

The ornamental design for a combined sofa-bed, drawer and bin, as shown and described.
